UNITED STATES PATENT OFFICE.

JOHN GELL, OF WELLINGTON, NEW ZEALAND.

APPARATUS FOR PERFORATING TAPE FOR AUTOMATIC TELEGRAPH INSTRUMENTS OR THE LIKE.

SPECIFICATION forming part of Letters Patent No. 751,164, dated February 2, 1904.

Application filed May 9, 1903. Serial No. 156,386. (No model.)

To all whom it may concern:

Be it known that I, JOHN GELL, a subject of the King of Great Britain, residing at Wellington, New Zealand, have invented certain new and useful Improvements in Apparatus for Perforating Tape for Automatic Telegraph Instruments or the Like, of which the following is a specification.

My present invention is an improvement upon the apparatus disclosed in Letters Patent of the United States No. 710,448, granted to me October 7, 1902, and upon that shown in applications for Letters Patent of the United States filed by me November 3, 1902, and respectively numbered 129,879 and 134,997.

I have sought by my present invention to simplify the apparatus and at the same time to render it certain in its operation, the action of the various groups of mechanisms taking place in proper order and each without interference with the action of any other group.

The features of improvement will be fully described hereinafter and particularly pointed out in the claims.

In the accompanying drawings, Figure 1 is a plan view of the apparatus. Fig. 2 is a sectional view from front to rear thereof. Fig. 3 is a detail sectional view along line 3 3 of Fig. 1, but with some of the parts in elevation. Fig. 4 is a detail sectional view on line 4 4 of Fig. 1 with some of the parts in elevation. Fig. 5 is a detail sectional view along line 5 5 of Fig. 1 with some of the parts in elevation. Fig. 5^a is a detail view relating to the tape-feed wheel and its presser-foot. Fig. 6 is a detail sectional view on line 6 6 of Fig. 1 with parts in elevation. Fig. 7 is a diagrammatic view of the electric connections of the apparatus. Fig. 8 is a detail view of the connection operated by the limiting-key. Figs. 9 and 10 are detail views of modifications. Fig. 10^a is a plan view, and Fig. 10^b a sectional view, of means for limiting the rise of the punches. Fig. 11 is a detail view relating to the parallel selecting-bars and their supporting means. Fig. 12 is a detail view of the punches and associated devices. Fig. 13 is a sectional plan view of the housing for the punches of the slider. Fig. 14 is a detail

bottom plan view of Fig. 12. Fig. 15 shows 50 the punches detached.

The arrangement of finger-keys is substantially the same as that disclosed in the patent and applications above referred to, and the key-levers 1 are fulcrumed at 2, so as to have 55 the same terminal lift. The key-levers operate vertical rods 3, guided in the frame and having selecting-combs 4 at their upper ends, said combs carrying rollers to engage and lift certain predetermined groups or combinations 60 of parallel bars, which are supported by links 6, pivoted thereto at their ends and pivoted also to the fixed frame of the machine. The movement of these parallel selecting-bars controls the operation of the various groups of 65 mechanism embodied in the machine.

The machine comprises a series of punches 7 for perforating the strip of paper or tape to represent the letter or character and to provide feed-holes and the spacing-hole. 70

It comprises also differential feed mechanism for the tape which advances the tape differentially, according to the number of ratchet-wheel holes or feed-holes in any particular letter. 75

The feed must be regulated differentially in order that the tape be moved forward the exact distance corresponding to the number of feed-holes used in the letter just punched.

In the cable-transmitter perforator to which 80 my invention appertains the spacing and marking or character holes utilize from one to five units of length, and it is necessary to regulate the feed according to the letter perforated.

Tape-feeding mechanism.—The tape is fed 85 by a star feed-wheel 8, having projecting points to engage the feed-holes of the tape. This star feed-wheel is on a shaft 9, journaled in bearings 10 under the top plate of the machine, said shaft having fixed thereto a lantern feed-wheel 11, engaged by a feed-pawl 12 on a feed-girder 13. The pawl is under tension of a spring 14. The feed-girder is hung on parallel links 15 and 16, one of which is pivotally supported on the feed-shaft 9, and 95 the other is pivoted at 17 below the top plate of the machine.

The feed-girder is pressed normally to the

right, Fig. 3, by a spring 18, connected to a pin 19, adjustably held by nuts 20 to a bracket 21 on the plate of the machine. Opposite the other end of the feed-girder there is a series 5 of stop-feed pins 22 22^b 22^c 22^d, arranged to be thrust singly, as will be hereinafter described, across the path of the feed-girder as it swings leftward, the function of said stop-pins being to arrest the feed-girder differentially, the several stop-feed pins being located, as shown, at different distances from the end 10 of the lever in normal position.

The feed of the tape takes place as a result of the movement of the feed-girder toward the right after it has been set against one or 15 the other of the pins, according to the number of feed-wheel holes in the letter.

In order to move the feed-girder toward the left to set it in position against the appropriate 20 stop ready for the feeding action, electromagnets 23 are employed, fixed below the top plate of the machine, Figs. 1 and 3, the pole 24 of which when the magnets are energized operates an armature-lever 25, pivoted at 26 to the cheeks 27, depending from the top plate, the said armature-lever being connected by links 28 with a suspended lever 29, pivoted at 30 in a housing 31 and having its lower end fitting between rollers 32 32^a on the 30 feed-girder.

Differential check for tape-feed mechanism.—Before the said feed-setting magnets 23 are energized, however, and before the feed-girder swings leftward to be set in position 35 for the feeding action the appropriate check or stop-feed pin 22^a to 22^d is thrust inwardly across the space between the cheek-blocks 27, Fig. 4, and across the path of the feed-girder.

For setting the check or stop-feed pins each 40 is connected with one of a series of tertiary levers 33, Fig. 4, pivoted at their upper ends in the casing 34. These are operated by angular secondary levers 35, having rollers bearing thereon, said secondary levers being in 45 turn operated by rollers on primary levers 36, pivoted at their front ends to the frame 37. There is one set of these levers, primary, secondary, and tertiary, for each of the check or stop pins, and the primary lever of each 50 set is operated from one of the parallel bars and a separate one from those operating the other primary levers. The connection between the parallel bars and the primary levers consists of stems or rods, as 38, extending 55 up from the parallel bar to the corresponding primary lever, Figs. 1 and 4. Each set of levers is returned to normal position when the key is released by a spring 33', connected to the tertiary lever.

60 I have marked the different sets of levers in Fig. 1, 36^a 36^b 36^c 36^d, corresponding to the check or stop pins 22^a, &c., operated by said different sets of levers. Stop-pin 22^a, for instance, is actuated from parallel bar a^{12} on

depressing the space-bar of the machine and 65 sets the feed-girder, so as to limit the travel of the tape to one ratchet feed-wheel hole. Parallel bar a^{12} actuates pin 22^b through its individual set of levers and limits the travel to two feed-holes. This bar is operated when 70 any key representing two feed-holes is depressed. Parallel bar a^{11} actuates stop-feed pin 22^c, representing letters having three feed-holes, and in like manner parallel bar a^{10} actuates stop-feed pin, so that the feed-girder 75 will be set to feed the tape four feed-holes, and when no stop-feed pin is thrust across the path of the feed-girder while on its leftward or setting movement the said girder will be arrested by the block 22^d, fixed between the 80 cheek-blocks 27, and when the feed-girder then moves from this position toward the right it will turn the lantern-wheel and star feed-wheel the maximum amount to feed the tape a distance equal to five feed-holes, so that 85 letters having five feed-holes have no rollers or teeth in their combs, and consequently none of the parallel bars controlling the check or stop-feed pins will be operated when a key representing a letter of this character is depressed. 90

The action of the parts as thus far described may be briefly stated as follows: Supposing a key is depressed representing a letter with two feed-holes, the first action will be to lift 95 the comb corresponding to the said lever, and as this comb has a tooth or roller under parallel bar a^{12} said bar will be raised, thus operating the series of primary, secondary, and tertiary levers of stop-feed pin 22^b, thrusting the 100 same across the path of the feed-girder. As soon as the stop-feed pin is set the feed-setting magnets 23 are energized, as will be hereinafter described, and the feed-girder is moved toward the left, Fig. 3, until it sets itself 105 against the feed-stop pin 22^b. As a result of this action the pawl on the feed-girder will slip back over the teeth or pins of the lantern-wheel, the said wheel, however, being held against movement by the spring-pressed 110 39. At this time also the reverse check-tooth 40 has been removed from the lantern-wheel by the swinging of the lever 29, and the parts are now set for the feeding of the tape. While the parts of the feed mechanism are in this set 115 position the punches are operated, as will be hereinafter described, and the tape is perforated, and as soon as this has been accomplished and the punches have been raised free from the tape the setting feed-magnets 23 are 120 deenergized and the spring 18 draws the feed-girder to the right, thus turning the lantern-wheel and the star feed-wheel an amount corresponding to the number of feed-holes the feed mechanism has been set for—in this instance two feed-holes—the movement being arrested by the reverse check-tooth 40 on the lever 29, which swings to engage and stop the 125

lantern-wheel as soon as the armature is released by deenergizing the setting-electromagnets.

Referring to Figs. 5 and 5^a, the tape-feed wheel has a rim 8^x, carrying the points and adjustably held on the wheel by the screws 8^a. A shoe 8' holds the tape into engagement with the parts on the feed-wheel, and this shoe is carried by a bracket 8.

10 *Punching mechanism.*—This mechanism, in so far as it relates to the punches and the mechanism for selecting the same, is substantially similar to that described in the applications above referred to, consisting generally 15 of a series of punches 7, made up of two kinds, those 7^x for the marking-holes and those 7 for the spacing or feed holes. These punches pass through a vertically-movable slider 41 and are adapted to be selected and interlocked 20 therewith in predetermined groups or series by interlocking pins 42, which pass through openings in the slider and into openings 43 in the punches. These interlocking pins are operated selectively from the selecting-combs 25 before mentioned through the appropriate parallel bars and through lever - and - link mechanism 44 and 45, as shown in Fig. 2, the said levers being suitably pivoted to the frame and being operated from the parallel bars by 30 the rods 46.

The passage-way for the tape is indicated at 47, and the punch or die plate, upon which the tape rests and through which the punches pass, is indicated at 48. The punches are arranged 35 in a housing or casing 7', and the slider 41 is guided to move vertically in the said housing. My improvement in this connection relates more particularly to the means for operating the slider with its interlocked punches so as 40 to perforate the paper. For this purpose perforating-electromagnets 49 are supported in a frame 50, secured to the under side of the top plate of the machine. The armature 51 of the electromagnets is carried by a lever 52, pivoted at 53 to a block 54, adjustably secured to the top plate of the machine. This lever is 45 made up of two side arms, which are pivotally connected to pitmen 55, which are in turn pivotally connected to the slider, so that when 50 the electromagnets are energized the armature will be drawn down and the slider will be depressed to force the selected punches through the tape for the formation of the marking-holes and the feed-ratchet holes.

55 After the electromagnets are deenergized a spring 56 will return the armature-lever and the slider and punches to their upper position ready for another operation.

At 57 I show an adjustable stop for the perforating action, this consisting of a cross-bar extending under the arms of the armature-lever and held by the hangers 58, extending up through the top plate and held by nuts 59, one of which is an adjusting-nut and the other 65 a set-nut.

In Figs. 10^a and 10^b I show a plate for limiting the upward movement of the punches, said plate 58' being adjustably held by screws 58" and 58^x to the top plate of the housing. The plate has holes, as shown in Fig. 10^a, for 70 the shanks of the punches to pass up through, while the shoulders on the said punches abut against the under side of the plate, and their rise is limited thereby.

Electric-circuit connection.—In Fig. 7 I 75 show a diagram of the electrical connections, electromagnets, and circuit-closing means. In this diagram the feed-setting electromagnets and the perforating-electromagnets are respectively connected to their contact-springs 80 b c and with the line-wire d of the battery, the other pole of which is connected to the circuit-closing-key lever e, which is provided with two points or nipples f g, of which that, f, for the setting feed-magnet circuit is higher 85 than that, g, for closing the perforating-magnet circuit, from which it results that when the circuit-closing-key lever is raised, as will hereinafter be described, the circuit of the feed-setting magnets will be closed first. The 90 feed mechanism will thus be set ready for the feeding action, after which the perforating-electromagnets will be energized, thus operating the punches, and as the circuit-closing lever moves down from the contacts b and c 95 it will leave c first, thus deenergizing the perforating-magnets, allowing the perforating-punches to rise from the tape under the action of the spring 56, and the circuit-closing lever next leaves the contact-spring b, thus deenergizing the tape-feed-setting magnets, allowing the feed-girder 13 to be moved toward the right by the spring 18, and thereby turning the lantern-wheel and star feed-wheel according to the number of feed-holes in the letter 100 or character just punched. The circuit-closing lever e and the spring-contacts b and c in practice are arranged as shown in Figs. 1 and 6, the lever e being pivoted to a bracket 59^x, secured to the frame of the machine by a screw 105 60, but insulated from the said frame by the vulcanite block 61 and collar 62. This lever is operated by the parallel bar a⁵, which is a universal bar in the sense that it is operated each time a key or the space-bar is depressed. 110 The said bar carries an anvil 63, which engages a roller 64 of insulating material on the circuit-closing lever. 65 is the binding post or screw for the circuit-wire. The contact-spring c is supported by a bracket 66, insulated, as at 67, from the machine-frame, and the binding post or screw for the circuit-wire is shown at 68. The contact-spring b is similarly arranged alongside the contact-spring c, as shown in Fig. 1. These contact-springs 115 extend over the nipples or points of the circuit-closing lever, as best indicated diagrammatically in Fig. 3, and their operation has been described above.

To briefly describe the sequence of opera- 120 125 130

tions in the machine, it may be stated that on depressing a key the following actions take place successively: A check or stop-feed pin is thrust forward across the path of the feed-girder to arrest its setting action. The feed-setting magnet is energized and the feed mechanism is set ready for action, corresponding in amount of feed to the number of feed-holes in the letter or character to be punched. The perforating-magnet is next energized, and the punches are thereby operated. The perforating-magnet is deenergized, allowing the punches to rise free from the tape. The feed-setting magnets are deenergized and the feed of the tape takes place under the action of the spring 18.

From the above it will be seen that the several actions take place in proper sequence and without conflict with each other. The differential check-pins and interlocking or punch-selecting pins are operated mechanically, while the feed-setting magnet and the perforating-magnets are included in simple circuits controlled by a single circuit-closing lever *e* and a single parallel bar.

By reference to Fig. 4 it will be noticed that as the primary lever 36 rises its roller moves farther from the pivot of the secondary lever 35 and the roller of this lever gradually moves away from the pivot of the tertiary lever 33, and as the roller of the secondary lever approaches the horizontal plane it of course has less effect on the tertiary lever 33, and this, together with the movement of the roller of the primary lever away from the pivot of the secondary lever, tends to give the maximum throw to the check or stop-feed pins at the beginning of the setting action, the movement of said pins gradually decreasing in speed until they are properly set in position. It will be seen that the forked end of the primary lever 36, extending beyond its roller, embraces a part of the secondary lever, and the forked end of this secondary lever in turn embraces the edge of the tertiary lever, thus keeping the levers in line and preventing lateral displacement.

The push rods or pins 38, which are selected by the parallel bars and in turn select the proper set of levers for setting the check or stop-feed pins in position, are carried by a slider or shifting plate 38^a. (Shown more clearly in Figs. 1 and 4.) This plate is connected with the lever 38^b, Figs. 1 and 8, pressed in one direction by a spring 38^c and having a connection 38^d leading to a limiting-key arranged similarly to the said key shown in the applications above referred to. By operating this limiting-key the slider or shifting plate 38^a may be adjusted so as to eliminate the spacing-hole in order that two groups of holes representing different characters may be printed without interruption or without spacing between them, so as to represent another character—such, for instance, as the interro-gation-point. For instance, supposing it is

desired to perforate the two sets of holes representing "A" and "O" contiguously, by depressing the limiting-key and then the "A" key the letter "A" is perforated; but on lifting the finger from the "A" key the tape will be advanced only two feed-holes instead of three, because the operation of the limiting-key has by shifting the plate 38^a caused the stop-pin 22^b to be set instead of the stop-pin 22^c, and if the "O" key is now depressed the perforations representing the letter "O" will be cut contiguous to those representing the letter "A" and without any space intervening, thus forming a composite character, which in the present instance is the figure "1."

In Fig. 9 I show an alternative arrangement for moving forward the check or stop-feed pins, whereby the roller on the end of the lever 36^x, corresponding to the primary lever, before described, moves against an inclined plane 38^a on the lever corresponding to the tertiary lever, so as to produce a prompt action at the first movement of the parallel bar and a gradually-lessening action at the latter movement of the parallel bar.

Referring to Fig. 10, it will be seen that the contacts *b* and *c* may be arranged one over the other instead of in the same horizontal plane, and the same successive closing of their respective circuits will result from this arrangement.

I claim as my invention

1. In combination in a perforating-machine, punching means, a tape-feeding roller, feeding means for operating the feed-roller, a setting-electromagnet for setting the said feeding means, stop-feed pins, a keyboard, lever connections between the said keyboard and the stop-feed pins and circuit-closing means controlled from the keyboard for controlling the setting-electromagnet, substantially as described.

2. In combination with a group of punches, a slider, interlocking pins to connect the punches with the slider in predetermined series or groups, and an electromagnet for operating the slider, substantially as described.

3. In combination with a group of punches, means for selecting said punches according to the key struck, an electromagnet, an armature-lever, connections between said lever and the punches and an adjustable stop for the punches acting on the armature-lever for limiting their movement under the pull of the electromagnet, substantially as described.

4. In combination with a group of punches, tape-feeding means, stop-feed pins, a feed-setting electromagnet for the feeding means to set the same in connection with the stop-feed pins, a perforating-electromagnet for operating the punches, circuit connections, contacts therein controlling the setting-electromagnet and the perforating-electromagnets, a circuit-closing lever, to operate the said contacts in succession, and means for actuating the tape-

feed means to feed the tape when the setting-electromagnet is deenergized, substantially as described.

5. In combination, a group of punches, means for selecting said punches according to the key struck, an electromagnet for moving the punches to perforate the paper and an adjustable stop for limiting the movement of the punches under the pull of the said magnet, substantially as described.

6. In combination in a perforating-machine, a group of punches, a perforating-electromagnet for operating the said punches, tape-feeding means, a feed-setting magnet, interlocking pins for the punches, a series of parallel bars, combs with connections to the finger-keys for operating the said parallel bars selectively, means for operating the interlocking pins from the parallel bars, electric contacts controlling the circuit to the feed-setting magnet and the perforating-magnet, said contacts being controlled by one of the parallel bars, substantially as described.

7. In combination, in a perforating-machine, a group of punches, a perforating-electromagnet for operating the said punches, tape-feeding means, a feed-setting magnet, interlocking pins for the punches, a series of parallel bars, combs with connections to the finger-keys for operating the said parallel bars selectively, means for operating the interlocking pins from the parallel bars, electric contacts controlling the circuit to the feed-setting magnet and the perforating-magnet, a circuit-closing lever controlling the said contacts, said lever being operated by one of the parallel bars, substantially as described.

8. In combination in a perforating apparatus, tape-feeding means, a setting-feed electromagnet, punching means, a perforating-electromagnet for operating the said punching means, check or stop-feed pins for giving a differential action to the said tape-feed means, a keyboard, lever connections between the said keyboard and the said check or stop-feed pins whereby the same are selected and set by the manual operation of the keys, lever mechanism for mechanically selecting the punches upon the operation of the keys, an electric circuit including therein the feed-setting electromagnet and the perforating-electromagnet contacts controlling the energizing of the said electromagnets in succession and means for closing the said contacts, substantially as described.

9. In combination in a perforating apparatus, a series of punches for perforating the tape, tape-feeding means, an electromagnet for controlling the tape-feeding means, an electromagnet for operating the punches, interlocking pins for selecting the punches to be operated, check or stop-feed pins for giving a differential feed to the tape-feeding mechanism, a series of parallel selecting-bars,

key connections thereto, lever connections between the selecting-bars and the check-feed pins and the interlocking pins whereby said pins are mechanically selected by the operation of keys, electric-circuit connections including the feed-controlling electromagnet and the punch-operating electromagnet contacts controlling the said circuit connections and a circuit-closing lever operated from one of the parallel bars to operate the contacts in succession, substantially as described. 65

10. In combination in a perforating-machine, tape-feeding mechanism, check or stop-feed pins and means for setting said pins in position, said means imparting a maximum throw to the said pins at the outset and which throw gradually decreases, substantially as described. 70

11. In combination in a perforating-machine, tape-feeding mechanism, check or stop-feed pins and means for setting said pins in position, said means comprising a plurality of levers, the end of the impelling-lever in each instance moving away from the pivot of the lever impelled, substantially as described. 80

12. In combination in a perforating-machine, tape-feeding mechanism, check or stop-feed pins and means for setting said pins in position comprising a set of levers for each pin, each set being composed of a primary, a secondary and a tertiary lever, substantially as described. 90

13. In combination in a perforating apparatus, tape-feeding means comprising a tape-feed wheel, a feed-girder, links supporting the same, one of which is supported axially of the tape-feed wheel, means for operating the feed-girder and check or stop-feed pins arranged to be struck by the end face of the said lever as it swings longitudinally, substantially as described. 100

14. In combination in a perforating-machine, a tape-feed wheel, a feed-girder, swinging links supporting the same, a lever 29 engaging the feed-girder, differential stop-pins at the end of the lever, an electromagnet and an armature-lever connected with the lever 29, substantially as described. 110

15. In combination in a perforating-machine, a tape-feed wheel, a feed-girder, swinging links supporting the same, a lever 29 engaging the feed-girder, differential stop-pins at the end of the lever, an electromagnet and an armature-lever connected with the lever 29, said lever 29 having a reverse check-tooth and a wheel operated by the feed-girder controlled by said check-tooth, substantially as described. 115

16. In combination in a perforating-machine, punching mechanism, a tape-feed wheel, a lantern-wheel connected therewith, a feed-girder, parallel links supporting the feed-girder, a pawl for turning the lantern-wheel, differential stop-pins at the end face 120

of the feed-girder, means for setting the said pins, an electromagnet, an armature-lever, a lever 29 connected to the feed-girder and having a reverse check-tooth to engage the lantern-wheel and a connection between the said lever 29 and the armature-lever, substantially as described.

17. In a perforating - machine, tape - feed mechanism, punches and electromagnets for acting upon tape-feed mechanism, the punches, contact-springs one arranged over the other and controlling the electric circuits in which the electromagnets are included and a circuit-closing lever for closing the circuits through the said springs in succession by first engaging with the lower contact with which said lever is normally out of contact and lifting the same to engage with the upper contact, substantially as described.
18. In combination in a perforating apparatus, punches and electromagnets, an armature-lever connected with the punches, an adjustable pivot for the armature-lever and an

adjustable U-shaped stop for the said lever, substantially as described.

25

19. In combination in a perforating apparatus, a tape - feed roller, a longitudinally-movable feed-girder, parallel links supporting the said girder, a pawl moving with the girder, and differential stop means for the said girder, substantially as described.

30

20. In combination with the punches, means for operating the same consisting of a slider and interlocking pins to fix the punches thereto and means for limiting the rise of the punches consisting of a perforated plate through which the shanks of the punches pass and means for adjusting the plate vertically, substantially as described.

35

In testimony whereof I affix my signature in presence of two witnesses.

JOHN GELL.
